UNITED STATES PATENT OFFICE

BRUNO BAUER, OF VIENNA, AUSTRIA

REINFORCED-CONCRETE COLUMN

Application filed September 10, 1927, Serial No. 218,637, and in Austria July 20, 1927.

This invention relates to a method of producing braced reenforced concrete columns and to improved columns so produced. The essential feature of the method according to the present invention consists in the employment of a unitary work piece, which comprises an iron core, a column head, a bracing member, a shell and a plaster carrier. The work piece can be fitted together ready for use in the foundry and thereafter carted to the place of erection. It can be readily used as support or standard and concreting can be carried out immediately without the necessity of employing the generally used auxiliary means for the production of reenforced concrete columns.

Several modes of carrying out the present invention are illustrated by way of example on the accompanying sheet of drawings, in which—

Figs. 1 and 2 show a work piece in longitudinal section and cross section respectively.

Figs. 3 and 4 illustrate a modified construction of the work piece in elevation and cross section respectively.

Fig. 5 shows in an enlarged scale the arrangement of the wire bracing member and the shell formed of corrugated sheet iron.

Fig. 6 illustrates diagrammatically another construction of a part of the work piece according to the present invention.

The work piece consists of an iron core of any convenient shape, which comprises four straps *a*, as shown in Figs. 1 and 2, or eight straps *a*, as illustrated in Figs. 3 and 4. On the iron core are slipped shell-supports, for instance annular or ring-shaped discs of sheet iron or the like, which determine the strength of the concrete column. In order to enable the slipping on of the discs, the iron core is provided with inwardly bent flanges *b*. In the illustration embodiments, the flanges are disposed only at the bottom end of the iron core, so that the discs can be slipped on from the bottom end.

In the construction shown in Fig. 6, the shell-support is formed by virtue of the fact that a sheet iron strip *c*, facing with its narrow side the iron core, is wound round the latter in screw-shaped windings.

Preferably corrugated sheet iron is used for the shell. The corrugated sheet iron may be wound round the iron core either in the shape of strips, or corrugated sheet iron plates may be employed. In order to dispose the bracing wires in the grooves of the corrugated sheet iron, the said grooves preferably extend at an incline, so that the same form screw-lines after the bracing of the iron core. The inclined positioning of the grooves is attained by virtue of the fact that the corrugated sheet iron plates are cut at an incline or that the edges are correspondingly displaced with respect to one another.

In the construction shown in Figs. 3 and 4, large corrugated sheet iron plates *d* are employed, which if desired extend over the whole height of the iron core. The wire-winding *e* passes in such a manner, that the wire rests in each groove.

In the construction shown in Figs. 1 and 2, two bracings are employed, one bracing resting at the outside in the grooves of the corrugated sheet iron, while the other inner bracing *f* rests tightly against the straps forming the iron core and extend in a straight line between the same.

As shown in Fig. 5, the corrugated sheet iron is provided with holes *g*, in order that during the concreting the air may escape and the raised parts of the corrugated sheet iron may be completely filled out with concrete, the said holes also facilitating the drying of the concrete.

The holes in the corrugated sheet iron may be formed by punching, so that the edges of the holes are jagged (Fig. 5) and serve for carrying the plaster.

In order to provide for an axial adjustment of a number of superposed columns, the

flanges *b* are furnished with projections *h*, which engage suitably shaped recesses *i* of the superposed column.

The end *k* of the column is provided with 5 slots *l* which are open at the top, in order to permit the insertion of the reenforcing bars for the beam from the top.

This construction possesses the further advantage, that the usual separate column-head, provided with a coping and lateral 10 openings for the pulling through of the re-enforcing bars, are dispensed with.

As shown in Figs. 1 and 3 of the drawing, the iron core is furnished at its upper end 15 with consols *m*, which serve as a rest for the shell of the roof construction.

I claim:

1. A work piece for a reenforced concrete 20 column comprising an iron core, shell supporting members carried by said core, a shell encasing said core and resting on said supporting members and bracing wires encasing said shell and retained in a definite position by said shell.

25. 2. A work piece for a reenforced concrete column comprising an iron core made up of a plurality of iron straps arranged in spaced relation and braced against lateral stress by bracing wires wound thereupon, 30 shell supporting members carried by said core, a shell encasing said core and resting on said supporting members and bracing wires encasing said shell and retained in a definite position by said shell.

35. 3. A work piece for a reenforced concrete column comprising an iron core, discs carried by said iron core for supporting a shell, a shell encasing said core and resting on the peripheries of said discs, bracing wires enclosing said shell, means on said shell for retaining said wires in a definite position and further means on said shell for retaining plaster.

45. 4. A work piece for a reenforced concrete column comprising an iron core, shell supporting means carried by said core, a shell encasing said core, a helical track formed on said shell, bracing wires resting in said helical track and outwardly protruding fingers 50 on said shell for retaining plaster.

55. 5. A work piece for a reenforced concrete column comprising an iron core, shell supporting means carried by said core, a shell encasing said core made up of diagonally corrugated sheet metal, bracing wires retained by the corrugations of said shell and struck-out fingers on said shell for retaining plaster.

65. 6. In a work piece for a reenforced concrete column, an iron core made up of a plurality of iron straps in spaced relation, the lower ends of said straps, having recessed portions and the upper ends of said straps, having protruding portions to mate said re-

cessed portions whereby said cores may be stacked in superimposed relation.

7. In a work piece for a reenforced concrete column, an iron core, shell supporting means carried by said core and a shell carried by said supporting means, said supporting means comprising a flat metal strip helically wound on said core, its one edge contacting said core and its other edge contacting said shell.

In testimony whereof I affix my signature.
Dr. BRUNO BAUER.
